UNITED STATES PATENT OFFICE.

KINNEY I. MILLER, OF LANCASTER, MISSOURI.

FEEDER SHIPPING BOX FOR CHICKS, ETC.

Application filed January 17, 1927. Serial No. 161,553.

This invention pertains primarily to boxes for use in shipping live chicks, rabbits, pigeons, guinea pigs and other small animals and fowls, where it is necessary or desirable to supply them while en route to their destination with feed and water.

More particularly, the invention provides a shipping box equipped with separate feed and water troughs, and convenient means for replenishing the same without removing the cover of the box. The invention further provides means for taking care of the drip or waste water in such a way that it will not run into the center of the box and so endanger the health of the stock carried.

Another object is to provide detachable feed and water troughs which may be readily mounted inside any conventional form of shipping box so as to adapt such box for the purposes stated.

The above stated objects and purposes, as well as other objects, will be fully understood from the following specification, considered in connection with the accompanying drawings, wherein

Figure 1 is a plan view of a box partly equipped with feed and water troughs as proposed by this invention, the cover of the box being removed and parts being broken out to clearly show the arrangement of the elements;

Figure 2 is a plan view of a box cover, showing the ports provided for the insertion of feed and water;

Figure 3 is a transverse section through the box, troughs and cover;

Figure 4 is a detail of one of the feed or water cups or troughs, which are made water-proof and inserted within the supports provided therefor;

Figure 5 is a plan view of a blank as cut from a sheet of material and adapted to be folded up to form one of the said feed or water troughs or cups, the folding lines being indicated by broken lines;

Figure 6 is a detail of a separable false bottom portion having a gutter incorporated at one edge thereof and so adapted for insertion at the regular bottom of the box, below the troughs, so as to catch any drip water and prevent the same running down amongst the stock carried;

Figure 7 is a plan view of a blank as cut from a sheet of material and adapted to be folded up to form one of the said separable

false bottom portions, the gutter lines being indicated by broken lines;

Figure 8 is an edge view of a modified and integrally formed insert for a conventional shipping box, which may be cut from a single sheet of material, and folded up to form and include all the essential features of the invention. The trough insert is also here shown in association with this element;

Figure 9 is a plan view of a blank as cut from a sheet of material ready for folding to form the insert described in Figure 8, the folding lines being indicated by broken lines;

Figure 10 is a detail view showing drain ports punched out through the sides of a conventional form of box immediately above the bottom thereof. This expedient is in lieu of the false bottom pieces embodying the gutters as shown in Figures 1, 3 and 6.

In carrying out this invention, I provide for the conventional shipping box 1, separable false bottom pieces 2, one for each of two opposite sides 3 of the box, and I form along one edge of these pieces crimps or gutters 4. The false bottom pieces 2 are cut to the length of the sides 3, inside measure, and are nicely fitted into the box and extended upon the regular bottom 5 thereof, with the gutters 4 opening upwardly and arranged flush against the sides 3 at the corners formed by those sides connecting with the bottom 5. Gutter outlet apertures 6 are cut through the lower corners of the other two sides 7, in alignment with the ends of the gutters 4, and so as to afford uninterrupted outlets for those gutters from the interior of the box 1. I next secure relatively long and narrow trough strips or plates 8 interiorly of the box 1, the same being spaced suitably from and arranged parallel to the said sides 3, with the lower edges 9 of these strips disposed upon the false bottom pieces 2 adjacent the gutters 4. As here shown the upper edges 10 of these strips 8 are flared inwardly of the box in a conventional trough formation, but the strips or plates 8 may be set straight with the sides 3 of the box if preferred. Within the space defined between the sides 3 and the strips 8, I insert water proofed troughs or cups 11. Relatively narrow guard strips or plates 12 are then secured vertically in place above the troughs 11, parallel to the sides 3, and are so arranged as to suitably

divide the spaces subtended between the upper edges of the trough strips 8 and the adjacent box sides 3; thus providing for the stock carried access openings 13, at the front 5 of the guard strips 12, into the troughs 11; and providing food and water chutes 14 formed between the strips 12 and the box sides 3, for the insertion of food and water down therethrough into the troughs 11. 10 The cover 15 of the box 1 is pierced with food and water ports 16 and 17 which are adapted to register with the chutes 14 when the said cover is properly mounted upon the box, and these ports are separately and distinctly marked with the words "Food" and "Water" as shown in the drawing.

The elements of the invention may be readily cut or formed from any suitable material, such as pasteboard, craftboard, strawboard or the like; and these elements may be secured in place within the conventional shipping box in any usual manner and as well known to artisans.

Figures 4 and 5 show how the feed and water troughs 11 may be readily formed from a sheet of material and folded up to serve the intended purpose. The blank 18 shown in Figure 5 is impressed with the folding creases 19 and straps 20 are extended as means for securing the troughs to the sides 3 of the box 1. This blank 18 is then easily folded up into the form shown in Figure 4. The troughs 11 may be rendered water-proof in any conventional manner.

Figures 6 and 7 show how the false bottom pieces 2 may likewise be formed from blanks 21 impressed with the gutter creases 22, and then bent up to form the gutters 4. 40 Figures 8 and 9 show a manner of forming a separable insert 23 from a single blank 24 impressed with folding creases 25, and having a food or water port 26 and a medial recess 27 cut therein. This blank may 45 then be folded up to form a ridge 28 which acts in lieu of the trough strip 8 to support the trough cup 11. The lower outer angle 29 of this integral element serves as a substitute for the gutter 4 of the first described structure, while the downwardly bent marginal portion 30 acts as a guard strip or plate in lieu of the other strip or plate 12. The cutting of the recess 27 forms 55 legs 31 adapted for insertion down into the ends of the gutter 29, through the end folds 32 of the trough 11, and affords a means for supporting the structure properly in place. The recess 27 itself gives the stock carried ready access to the food and water within the troughs 11. The vertical back portion 33 and the horizontal apron portion 34 of the insert 23 are suitably secured to a side 3 and the bottom 5 of the box 1, thus locking the insert in place with the port 60 26 of the upper connecting web 35 in align-

ment with a food or water port 16 or 17 of the cover. Of course this structure 23 is duplicated for both sides of the box, so as to enable serving both food and water to the stock carried.

Figure 10 shows a means for providing drainage for the said watering device, which may be readily formed in a conventional shipping box, by merely punching out drain ports 36 through the sides of the box immediately at the bottom thereof and below the said water trough 11.

In use proper directions are printed upon the cover of the box containing the shipment of chicks, or whatever it may be, instructing the transportation agent to feed and water the stock at stated times. This is accomplished by his inserting the food and water through the ports so marked, as aforesaid, whereupon it falls into the troughs. The guard strips or plates 12 act to hold back the surplus food from rolling out over the front edge of its trough 11; and to prevent the water from unduly splashing in its trough 11. It is thought best to provide water-proofed troughs for both food and water, so that in case the agent should pour water by mistake down the food port, the said water would be prevented from running out over the bottom of the box and in the midst of the stock, to the danger of their health. Whatever drip water there may be, overflowing the troughs 11, will run into the gutters 4 and out through the outlet 6, thus keeping the stock 100 relatively dry.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. In combination with a shipping box for small live stock, a trough arranged within the box at one side thereof; and a gutter arranged below the trough.
2. In combination with a shipping box for small live stock, a trough arranged within the box at one side thereof; and a gutter arranged below the trough, the said box having drain apertures cut through the sides in alignment with the ends of the said trough.
3. In combination with a shipping box for small live stock, a trough arranged within the box at one side thereof; a gutter arranged below the trough, the said box having drain apertures cut through the sides in alignment with the ends of the said trough; and the cover of the box having a feeding port cut therein over the said trough.
4. In combination with a shipping box

- for small live stock, a feeding trough arranged within the box at one side thereof; and a guard strip mounted above the trough, the said guard strip serving to vertically and longitudinally divide the trough to form access openings at the front of the strip and food and water chutes at the back thereof. 5
5. In combination with a shipping box for small live stock, a feeding trough arranged 10 within the box at one side thereof; and a guard strip mounted above the trough, the said guard strip serving to vertically and longitudinally divide the trough to form access openings at the front of the strip and 15 food and water chutes at the back thereof; the cover of the box having a feeding port cut therethrough over the said trough.
6. In combination with a shipping box for small live stock, a feeding trough arranged 20 within the box at one side thereof; a guard strip mounted vertically above the trough so that its lower edge divides the space between the upper edge of the trough and the side of the box; a gutter arranged 25 below the trough, the said box having drain apertures cut through the sides in alignment with the ends of the said gutter.
7. In combination with a shipping box for small live stock, a feeding trough arranged 30 within the box at one side thereof; a guard strip mounted vertically above the trough so that its lower edge divides the space between the upper edge of the trough and the side of the box; a gutter arranged below 35 the trough, the said box having drain apertures cut through the sides in alignment with the ends of the said gutter; and the cover of the box having a feed port cut therethrough adapted to be positioned over the said feed trough immediately back of 40 the said guard strip.
8. In a feeding or watering device for a
- shipping box, a false bottom piece arranged within the box at the bottom thereof, the said piece having a gutter formed therein 45 along one edge, the said gutter being disposed adjacent one side of the box.
9. In a feeding or watering device for a shipping box, a false bottom piece arranged within the box at the bottom thereof, the 50 said piece having a gutter formed therein along one edge, the said gutter being disposed adjacent one side of the box, the said box having apertures cut through its sides in alignment with the ends of the said 55 gutter.
10. A shipping box for small live stock, the said box having drain ports pierced through its sides immediately above the bottom, as means for draining the box. 60
11. A shipping box for small live stock, the said box having drain ports pierced through its sides immediately above the bottom, as means for draining the box; and a trough arranged within the box above said 65 drain ports.
12. A blank for an insert for a shipping box for small live stock, the same being formed from an integral sheet of material and adapted to fold up to form a bottom 70 apron, a feed trough supporting ridge and gutter, a vertical back portion, an upper horizontal connecting web and a depending guard strip interposed between the trough supporting ridge and vertical back portion, 75 the said connecting web having a feeding port cut therethrough.
13. A blank for a false bottom piece for a shipping box for small live stock, the same being formed from an integral sheet of material and adapted to fold up along one edge thereof to form a gutter. 80

In testimony whereof I affix my signature.
KINNEY I. MILLER.
